UNITED STATES PATENT OFFICE

VAN A. WALLIN, OF CHICAGO, ILLINOIS, ASSIGNOR TO AMERICAN HAIR & FELT COMPANY, OF CHICAGO, ILLINOIS, A CORPORATION OF ILLINOIS

FELT MANUFACTURE

Application filed March 29, 1928. Serial No. 265,598.

The invention relates to felt manufacture.

In the ordinary and usual process of manufacturing soft felts, such as are used for heat and cold insulation, cushioning and similar purposes, by the laid felt process where coarse fibres are used, such as hair and jute, and particularly in the process of manufacturing soft hair-felt, it is impracticable to manufacture successfully a thin sheet of felt, that is, a felt whose thickness is much below a quarter of an inch. This is due to the fact that soft felts, made of coarse fibres such as hair and jute, are of necessity low cost products made to compete with other cheap cushioning and heat insulating materials, such as flax, straw, wood fibre and cotton linters. To reach these low costs the fibres must be picked, carded, formed into bats and compacted or felted with heavy, coarse, mechanical equipment, including cards, lappers, platens, etc., designed to handle fibres in large quantities, such equipment differing very materially from the similar but finer and lighter machinery of much smaller capacity used in the manufacture of higher grade materials, such as fulled hair felts, cotton felts and wool felts. The lighter, finer machinery is designed to handle thin felt while the heavy equipment is designed to handle coarse materials made into thick felt.

In the use of this coarser machinery it is impracticable to lay a thin bat of hair or jute or other feltable fibres under the usual methods with sufficient uniformity to produce a marketable piece of felt. The bat, in the process of manufacture, is subjected to heavy pressure and violent vibrations, which are essential to the massive felter plates used in the manufacture of relatively thick insulating hair felts and other soft felts made of similar coarse materials. The pressure and the tearing action due to the weight and agitation of the platens or felt plates tend to destroy the thin bat instead of compacting it, the resulting products being liable to be torn or broken, or very uneven in thickness and, as stated, in common practice no attempt is made to produce thin felts through the use of the ordinary large size mechanical equipment.

ment built for the manufacture of soft hair felt.

The object of the present invention is to provide a simple, practical, efficient method for successfully manufacturing thin felts with the heavy, coarse machinery used in the manufacture of thick felts.

In the drawings Fig. 1 is a view through a felting apparatus illustrating my method, parts being broken away;

Fig. 2 is a detail end view of the material at an intermediate stage of manufacture.

I have discovered that the unsatisfactory product resulting in an attempt to manufacture thin felt by the use of heavy felting equipment, such as the fixed platen 3 and the vibratory felter plate 4 can be avoided by laying two or more thin bats 5 together one above the other with a separator 6 between the same, placing these bats with the interposed separator between the platen 3 and the plate 4 and subjecting the several layers to the pressure and vibration of the felter plate at one operation. The effect of the several layers of superimposed bats and separator or separators is to cushion each other from the disintegration that results when a single thin bat is placed under the felter plate alone. After the several layers or bats have felted or hardened under the felter plates, by the method above described, they are separated into individual units merely by peeling off the top bat 5 or sheet of felt and then alternately peeling off the intervening separator 6 and the sheets 5 of felt as they are exposed. These thin felt sheets 5 may then be dried, trimmed and cut as desired. The separator 6 may be of any suitable thin material capable of transmitting the vibratory pressure and preventing undue adhesion or penetration of the feltable fibres to or into its faces and I prefer to use fine mesh burlap, muslin, sheeting or paper for this purpose.

What I claim as my invention is:

The method of producing felts, made of hair, jute or other coarse, feltable fibres, too thin to be felted between the felter plates of the usual heavy felting machine, which consists in building up a composite mass of thin bats of the feltable fibres, separated from each

other by a single, thin, flexible separator, to a thickness sufficient for efficient handling in the usual heavy, coarse, felting machinery used in the manufacture of thick felts, subjecting the composite mass to the pressure and agitation of the felter plates at one operation, and after felting removing the separators.

In testimony whereof, I affix my signature.

VAN A. WALLIN.
